WASHING MACHINE

John J. Geiger, San Bernardino, Calif.

Application June 28, 1948, Serial No. 35,623

6 Claims. (Cl. 68—140)

1
This invention relates to improvements in washing machines and more particularly to that class which is adapted for household and other general use.

The primary object of the invention is to provide a washing machine with a rotary washing receptacle in which clothes and other material to be washed and dried are held, said receptacle being compensated while in motion to counteract and reduce unevenness of load, vibration and jar automatically.

Another object is to improve the construction of a washing machine so as to increase its utility and widen its field of usefulness and application.

Another object is to reduce excessive wear, simplify construction and provide means by which the various parts of the machine can be shifted into and out of operation under the control of an operator.

Among other objects is the production of a washing machine of its kind which is adapted to wash and dry material in an efficient manner, in a minimum of time and with minimum of wear and effort.

Other objects will be apparent from the following description of which the accompanying drawings form a part.

Fig. 1 of the drawings is a front elevation of my improved washing machine showing the outer shutter of the service passageway entering the washing material tumble barrel or drum, in wide open position; Fig. 2 is a vertical section taken substantially on the line 2—2 of Fig. 1, when the door, which normally closes the service passageway entering the tumble barrel is closed; Fig. 3 is a vertical section taken substantially on line 3—3 of Fig. 2; Fig. 4 is a section of a detail at enlarged scale taken approximately on the line 4—4 of Fig. 3; Fig. 5 is a section of a detail taken on the line 5—5 of Fig. 4, and Fig. 6 is an end view of the inner cylindrical resiliently supported cylindrical tumble barrel.

Referring to the drawings, my improved washing machine is shown having a rectangular cabinet or housing A constructed out of thin sheet metal or other suitable material and containing a closed rigidly held cylindrical tub B which is disposed on a horizontal axis in the chamber within the cabinet. The cabinet has an inner vertical back wall 13, top wall 14, opposite side walls 15—16 and a horizontal floor 16. Casters 17 are mounted below the floor 16 to enable the washing machine to be easily moved and a pneumatic suction cup 18 is vertically movable below and on the cabinet to enable the latter when the

suction cup is lowered to be maintained in stationary position on a supporting surface.

The tub B is capable of normally holding washing liquid and has a cylindrical side wall 19 and integral back and front end walls 20 and 21, all of said walls being solid, that is unperforated. The back end wall is journaled by the bearing 22 on the horizontal sleeve 23 and in the bearing 24 behind the back wall 13 of the cabinet. The front end wall 21 is journaled on the annular bearing 25 which is held rigidly within the circular door frame 26 on the front end wall of the cabinet. The door frame 26 forms a front entrance entering the tub and washing material tumble barrel C. The tumble barrel C is cylinder like and rotatable in the tub with its axis disposed horizontally, said tub B, bearing sleeve 23 and bearings 24 being horizontally and coaxially disposed in the cabinet.

20 The tub B has an orifice or mouth 30 in its side through which soap or washing compound can be admitted thereto or the liquid content of the tub can be emptied. For this purpose the tub is adapted to be reciprocated into two positions,

25 one when the opening 30 registers upwardly with a fixed spout 31 in the cabinet through which soap is adapted to be deposited into the tub and the other when the liquid washing content of the tub is emptied into a compartment 32 in the

30 lower portion of the cabinet and is allowed to egress through an outlet 33 in the floor of the cabinet. The reciprocation of the tub as stated is accomplished through a pulley rim 34 mounted on the perimeter of the tub and a drive pulley

35 which is adapted to be actuated through hand controlled suitable transmission represented by 38 and the motor 39. The transmission may be of any desired type and is adapted to be hand controlled to either reciprocate the tub as described or to revolve the tumble barrel C continuously as hereinafter described. The opening

30 in the tub is provided with outwardly projecting flanges 40 and 41 which are adapted to respectively strike stops 42 and 43 and limit the

45 reciprocable movement in either direction when the opening 30 registers in upward or downward position as stated. The flanges and opening in the tub are shown in full line position in Fig. 3 when the tub assumes a position suitable for emptying. When the tub is rotated in the direction of the arrow shown in Fig. 3, its opening 30 can be made to register with spout 31 and the washing operation then carried on.

The sleeve 23 is an integral part of the driving disk member 45 of the washing machine

3

tumble barrel holder and is journaled on a fixed horizontal tubular spindle 46. Said spindle is held rigidly on a bracket 47 which is supported by the cross beams 48 on the back wall 13 of the cabinet. The connecting portion between the inner end of the sleeve 23 and said driving disk 45 of the tumble barrel holder is slightly conical and points inwardly into the central portion of the tumble barrel C, thus functioning like a nozzle. This nozzle portion of the tumble barrel holder is journaled by the bearing 49 on the spindle. Washing liquid is adapted to be sprayed into the central portion of the tumble barrel on the washing material therein while the tumble barrel is revolving or stationary through the spindle 46 and is controlled by valve 50, said valve being opened or closed by the operating handle 51 and stem 52. A suitable source of water or other liquid supply at suitable temperature is admitted into the tumble barrel through the pipe connection 53 and spindle. A drive pulley 54 is rigidly secured to the end portion of sleeve 23, said pulley being driven by the belt and pulley connections 55 and 56, motor 39 and transmission 38. In this manner the tumble barrel C is adapted to be revolved and operated under the control of an operator.

The tumble barrel C is of general cylindrical shell form having a cylindrical side wall 58 composed of thin perforated material and formed with inturned back and front end walls 59 and 60. The rims at the opposite ends 59 and 60 of this cylindrical shell are formed with broad annular horizontal back and front circumscribing bearing seats 61 and 62 and said shell 58 is also formed at circumferentially spaced intervals apart with a plurality of inwardly directed longitudinal paddle members 63. These paddle members may be of suitable cross sectional contour (Fig. 5), having inwardly tapering opposite side walls 64 and 65, a flat inner portion 66 and open ends, thus forming transverse channels 67, directed inwardly towards the axis of the barrel. As many of these circumferentially arranged transverse paddles may be employed as desired, their function being to agitate, scrub and beat the washing material which is held in the tumble barrel as the latter is revolving.

The support for the tumble barrel has a driving disk member 45 and a cooperating opposite front end disk-like member 68 (Fig. 4), the latter circumscribing the front doorway. These two members 45 and 68 are rigidly connected at circumferentially spaced intervals apart corresponding with the paddles 63 by pairs of longitudinal channel members 69 and 70, which are fastened at their opposite ends to said end members 45 and 68, there being a pair of said channel members disposed in each paddle. Each pair of channel members has a longitudinal flat spring member 71 secured thereto with its arms projecting inwardly towards the axis of the tumble barrel. These spring arms are of substantially equal tension so that the cylindrical shell member 58 of the tumble barrel normally rides on a spring support coaxially in the tub with its outer periphery slightly spaced from the periphery of said holder. The channel members 69 and 70 and spring 71 of each unit also assist in transmitting rotary motion to the cylindrical tumble barrel member as the latter rides freely thereon. The end members 45 and 68 for freely supporting the tumble barrel are formed with peripheral inturned outer bearing rims 72 and 73 which cooperate respectively with

4

the inner bearing rims 61 and 62 in forming annular bearing channels at the opposite ends of the cylinder-like tumble barrel in which endless circular rubber-like compensating tubes D are held. These tubes are filled with any suitable fluid medium such as water or air and function to counteract uneven load of the washing material and washing liquid held in the tumble barrel and also compensate and subdue any vibration and jar caused by the revolution of the tumble barrel. This means of articulating the portions of the tumble barrel and cushioning the load thereof as it revolves either forwardly or backwardly is highly effective in operation and subdues any tendency approaching uneven action, vibration and jar during the operation of the washing machine.

Any suitable door structure may be employed for closing and opening the front entrance, that shown having an outer pivoted frame 23 enclosing a glass panel which constitute an outer door 74. An inner hinged electrical heating door member 75 is also shown in the doorway through which a current of air is heated and circulated by forced draft, the latter being activated by the electric fan 76 and circulated through the chamber within the tumble barrel to dry the washing material after the washing liquid has been drained from the tub and while the entrance into the tub is in upward registration with the spout 31 and the tumble barrel revolves.

While I have shown and described my improvements as applied to a construction in which the tumble barrel revolves about a horizontal axis, it is to be understood that the construction can be modified and the tumble barrel disposed to revolve about an inclined or vertical axis within the spirit of the invention.

In accordance with the patent statutes I have described the principles of operation of my invention together with the construction thereof which I now consider to represent the best embodiment thereof, but I desire to have it understood that the construction is only illustrative and that the invention can be carried out by other means and applied to uses other than those above set forth within the scope of the following claims.

I claim:

1. In a washing machine, a stationary casing having a service opening in one end thereof and an outlet in its side, a cylindrical tub rotatively supported about a horizontal axis within said casing and having a side delivery opening for washing material and a pair of rotatable holders coaxially journaled in the tub and casing and having corresponding supporting perimeters, a drum having a perforated annular side wall and its end portions retained within said supporting perimeters, and means for dampening vibration between said supporting perimeters and the end portions of said drum.

2. In a washing machine, a stationary casing having a service opening in one end thereof, a cylindrical tub rotatively supported about a horizontal axis within said casing and having an end service opening in registration with the end opening in said casing and a side delivery opening for washing material, a pair of rotatable holders coaxially journaled in the tub and casing, and having corresponding supporting perimeters, a drum having a perforated annular side wall and its end portions retained within said supporting perimeters, and means for dampening vibration

between said supporting perimeters and the end portions of said drum.

3. In a washing machine, a stationary casing having a service opening in one end and in one side thereof, a cylindrical tub rotatively supported about a horizontal axis within said casing and having an end service opening in registration with the end opening in said casing, a pair of spaced end holders coaxially rotatable in the tub and casing, a tumbling drum having a perforated side wall and its opposite ends retained in said pair of holders, and annular resilient tubes interposed between said end holders and the end portions of said drum by which shock and vibration produced by the revolution of the drum and tumbling of washing material therein is cushioned.

4. In a washing machine, a stationary casing having a service opening in one end thereof and a side service passage, a cylindrical tub rotatively supported about a horizontal axis within said casing and having an end service opening in registration with the end opening in said casing and a side service passage adapted to register with said side service passage in said casing, a pair of holders coaxially journaled in the tub and casing and having inturned peripheral flanges, a tumbling drum having a perforated cylindrical side wall within said flanges, and circular cushioning tubes interposed between the flanges of said holders and engaging portions of the circular side wall of said drum.

5. In a washing machine, a stationary casing having service openings in one end and one side thereof, a cylindrical tub rotatively supported about a horizontal axis within said casing and having end and side service openings adapted to register respectively with the end and side service openings in said casing, disk holders coaxially journaled and spaced apart horizontally on the casing and tub and having a pair of inturned peripheral flanges, a tumble drum coaxially disposed and rotatively mounted in said tub and having a perforated annular side wall extended

within said flanges, and circular cushioning elements between the end portions of the tumble drum and said flanges by which jar and vibration produced by the revolution of the drum and tumbling of washing material therein are reduced.

6. A washing machine, comprising a casing having a service passage in one end thereof, a cylindrical tub rotatively supported in said casing about a horizontal axis and having a service opening adapted to register with the service passage in said casing, rotatable holders coaxially journaled in the tub and casing, a cylindrical tumble drum mounted upon said holders and revolved thereby, said drum having a perforated side, an end service opening corresponding with the service opening in said tub and longitudinally inwardly directed paddles disposed at circumferential intervals in said drum, and annular cushion tubes interposed between the opposite peripheral end portions of said tumble barrel and said flanges in said holders by which vibration and shock produced by said drum and tumbling of washing material therein is damped.
